UNITED STATES PATENT OFFICE.

JAMES T. JOHNSON AND THOMAS THOMPSON, OF WHAT CHEER, IOWA.

COAL-DRILLING MACHINE.

SPECIFICATION forming part of Letters Patent No. 321,034, dated June 30, 1885.

Application filed April 22, 1885. (No model.)

To all whom it may concern:

Be it known that we, JAMES T. JOHNSON, and THOMAS THOMPSON citizens of the United States, residing at What Cheer, in the county 5 of Keokuk and State of Iowa, have invented a new and useful Improvement in Coal-Drilling Machines, of which the following is a specification, reference being had to the accompanying drawings.

10 Our invention relates to an improvement in coal-drilling machines; and it consists in the peculiar construction and combination of devices that will be more fully set forth herein-after, and particularly pointed out in the 15 claims.

15 In the accompanying drawings, Figure 1 is a top plan view of a machine embodying our invention. Fig. 2 is a side elevation of the same. Fig. 3 is a vertical sectional view taken 20 on the line *x x* of Fig. 1. Fig. 4 is a transverse vertical sectional view taken on the line *y y* of Fig. 1.

25 A represents a supporting-bar for the drilling-machine, which has one end flattened, as at *a*, and is provided with projecting steel points or spurs *b*. The bar is secured in place by inserting its flattened end in a hole drilled in the coal and a wedge, *c*, which forces the spurs into the coal and securely holds the bar 30 in place. To the outer end of the bar is swiveled a bracket, *B*, by a bolt and nut, *C*. The bracket *B* has two lugs, *D*, provided with aligned openings, in which are journaled the frame of the machine; and in one of the lugs 35 is made a quarter-circular slot, *E*, through which passes a set-screw, *F*, that enters the frame and secures it in the bracket at any desired angle, while by having the bracket swiveled to the end of the supporting-bar the frame 40 can be turned to any desired point of a circle. The frame *G* has trunnions *H*, that enter the openings in the lugs of the bracket and journal the frame therein. The front end of the frame is provided with a curved extension, *I*, that 45 forms a bearing for a shaft, *K*, to the inner end of which shaft is fixed a miter-gear pinion, *L*, and to the outer end of which is secured a crank, *M*. The frame *G* has a hinged upper portion, *N*, and is provided with an inferiorly-screw-threaded opening, which passes 50 longitudinally through the frame, between it and the hinged portion *N*. Through this open-

ing passes a threaded rod, *O*, which has a bit-stock, *e*, at each end, and to which is feathered or splined a miter-spur wheel, *P*, with which the pinion *L* engages. An auger, *R*, is secured in one end of the rod *O*. When the crank is turned, the auger is fed forward, as will be readily understood.

A drilling-machine thus constructed is compact, cheap, and simple, is easily operated, and can be inclined and turned so as to be used at any desired angle. By lifting the hinged portion of the frame the threaded rod may be removed at any time, and the machine 65 is so constructed as to be readily taken apart and packed for transportation in a very small space.

We are aware that it has been heretofore proposed to construct drilling-machines that 70 are adapted to be inclined and turned, so as to work the drill at any desired angle, and this, broadly, we disclaim.

Having thus described our invention, we claim—

1. The combination of the supporting-bar, the bracket *B*, swiveled thereon, the frame *G*, journaled in the bracket, and having the curved extension or arm *I*, the screw *O*, working in the frame, the mitered gear-wheel *P*, feathered or splined on the screw, the mitered pinion *L* on a shaft journaled in the arm *I* and meshing with wheel *P*, and a crank for rotating the pinion, substantially as described.

2. The combination of the supporting-bar, 85 the bracket *B* swiveled thereon, having the lugs *D*, and the segmental slot *E* in one of said lugs, the frame *G*, journaled in the bracket and having the curved arm *I*, the screw *O*, working in the frame, the miter-gear wheel *P*, feathered on the screw, the miter-pinion *L* on a shaft journaled in arm *I*, and meshing with wheel *P*, a crank for rotating the pinion, and the set-screw *F*, passing through slot *E* and entering frame *G*, for the purpose set forth, substantially as described.

In testimony that we claim the foregoing as our own we have hereto affixed our signatures in presence of two witnesses.

JAMES T. JOHNSON.
THOMAS THOMPSON.
